UNITED STATES PATENT OFFICE.

JAMES G. MACLAREN, OF WEEHAWKEN, NEW JERSEY, ASSIGNOR TO LAMSON CONSOLIDATED STORE SERVICE COMPANY, OF NEWARK, NEW JERSEY, A CORPORATION OF NEW JERSEY.

PNEUMATIC-DESPATCH-TUBE APPARATUS.

977,110.

Specification of Letters Patent. Patented Nov. 29, 1910.

Application filed March 25, 1908, Serial No. 423,180. Renewed June 20, 1910. Serial No. 567,999.

To all whom it may concern:

Be it known that I, JAMES G. MACLAREN, of Weehawken, in the county of Hudson and State of New Jersey, have invented certain new and useful Improvements in Pneumatic-Despatch-Tube Apparatus, of which the following is a specification.

My invention relates to improvements in pneumatic despatch tube apparatus and its object is to provide means for controlling and limiting the flow of air through the transmission tubes to the interval necessary for the transmission and delivery of carriers and for automatically switching or short circuiting the flow of air from the transmission tubes to the atmosphere when the carriers have delivered thereby reducing the resistance and unloading the blower or pump and consequently effecting a saving of power.

In the accompanying drawings is illustrated a form of construction embodying my invention in which,—

Figure 1 is a diagrammatic view of the apparatus. Fig. 2 is an enlarged sectional elevation of a portion of Fig. 1 showing the normal position of the controlling mechanism. Fig. 3 is a similar view to Fig. 2 showing the position of the mechanism when a carrier is in transmission.

Like letters of reference refer to like parts throughout the several views.

A is a tube for the transmission of carriers and connects the central station C with the terminal D controlled by the ordinary delivery valve D' at sub-station S.

B is a tube for the return of carriers and connects the terminal D at sub-station S with the terminal G controlled by the valve G' at central station C.

F represents a bell-mouth or air inlet for despatching carriers in tube A and E is an ordinary inlet for inserting carriers into the tube B.

M represents an electric motor adapted to drive the blower J through a belt M' at a constant speed and H is a conduit or air tube connecting the blower J with the terminal G.

N is a casing having mounted therein the diaphragm N', said casing above said diaphragm being connected with the conduit H by a tube K and with the atmosphere by a branch tube L having an air inlet or open-

ing L'. The valve N³ adapted to control the air inlet L' is mounted on the lower end of the diaphragm stem N² and carries the weight N⁴. The casing N beneath the diaphragm N' is connected by the passage P with a casing R having a chamber S' normally closed from said passage P by a valve R' actuated by the spring R⁴. Mounted in the chamber S' is a diaphragm R² connected with and adapted to operate the valve R' through a link R³. R⁵ is a chamber located above the diaphragm R² and connected with the chamber S' by means of the bypass R¹⁰ controlled by the timing valve R¹¹. R⁶ is a port for admitting air to chamber R⁵ and is controlled by a valve R⁷ mounted on one end of the bell-crank lever R⁹ and which valve is held normally closed by spring R⁸. On the opposite arm of lever R⁹ is an armature T' adapted to be operated by a magnet T, which magnet is in circuit with the battery Z and switch c at central station C through wires 1, 2 and 3, the switch s at sub-station S being connected in multiple through wires 4 and 5.

The operation of the device is as follows,—The motor M drives the blower J at a constant speed and with no carriers in transit the parts are in the position shown in Figs. 1 and 2, air being taken in through tube L pipe K and conduit H to the blower J permitting the blower to operate normally unloaded. If it is desired to despatch a carrier from central station C to sub-station S the operator inserts the carrier into the bellmouth F and closes the switch c which energizes the magnet T attracting the armature T' and opening the valve R'. The valve N³ normally offers sufficient resistance to the air entering the tube L to create a vacuum in the casing N above the diaphragm N' to hold said valve N³ open and this vacuum existing in chamber S' has exhausted the air from chamber R⁵ through bypass R¹⁰. The opening of the valve R⁷ destroys this vacuum in chamber R⁵ allowing the diaphragm R² to be drawn down by the vacuum in chamber S' and through link R³ opening the valve R' against the action of spring R⁴ and admitting the vacuum to the casing N beneath diaphragm N' which in conjunction with weight N⁴ closes the valve N³ cutting off the

flow of air through the tube L. The operator now releases the switch c deenergizing magnet T and permitting the valve R⁷ to close. The air now entering through bell-mouth F drives the carrier through tube A toward sub-station S. Upon the closing of valve R⁷ the admission of air is cut off and the vacuum in chamber R⁵ is gradually restored through bypass R¹⁰ and timed by valve 10 R¹¹ so that by the time the carrier has delivered at sub-station S the valve R' has been closed by spring R⁴ cutting off the vacuum from the under side of diaphragm N'. The vacuum above the diaphragm N' now acts 15 to lift said diaphragm and valve N² short circuiting the flow of air through the opening L' and tube L relieving the load upon the blower.

In despatching a carrier from sub-station 20 S to central station C, the operator opens the inlet E inserts the carrier into the tube B and momentarily closes the switch s which energizes the magnet T and opens the valve R⁷ destroying the vacuum in chamber R⁵ 25 and causing valve R' to open and the diaphragm N' to be drawn downward closing valve N² as heretofore described. The air now enters through bellmouth F and tube A and drives the carrier through tube B until 30 the carrier has delivered at station C and the flow of air short circuited through the tube L and the blower unloaded as described.

Having thus described my invention and set forth a construction embodying the same, 35 what I claim as new is—

1. In a pneumatic despatch tube apparatus, a tube for the transmission of carriers, a blower or pump, a connection between said transmission tube and said blower or pump, 40 a branch tube or air inlet in communication with said connection, a valve adapted to control the flow of air through said air inlet, mechanism operated on one side by the blower for normally holding said valve open 45 to admit air to said inlet thereby short circuiting the flow of air to and relieving the load upon said blower, and means for causing the blower to act on the opposite side of said mechanism to close said valve to cut off 50 the flow of air through said inlet and switch the same through said transmission tube for driving carriers.

2. In a pneumatic despatch tube apparatus, a tube for the transmission of carriers, a blower or pump, a connection between said transmission tube and said blower or pump, a branch tube or air inlet in communication with said connection, a valve adapted to control the flow of air through 60 said air inlet, mechanism operated on one side by the blower for normally holding said valve open to admit air to said inlet thereby short circuiting the flow of air to and re-

lieving the load upon said blower, means for causing the blower to act on the opposite 65 side of said mechanism to close said valve to cut off the flow of air through said inlet and switch the same through said transmission tube for driving carriers, and time controlled means for restoring said valve to normal or open position.

3. In a pneumatic despatch tube apparatus, a tube for the transmission of carriers, a blower or pump, means for driving said blower or pump, a connection between 75 said blower or pump and said transmission tube, a branch tube or air inlet in communication with said connection, a valve adapted to control the flow of air through said air inlet, a diaphragm connected with said valve 80 and adapted to be actuated by the blower on one side to hold said valve normally open thereby short circuiting the flow of air to and relieving the load upon said blower, a normally closed passage connecting the opposite side of said diaphragm with said blower, and means for opening said passage 85 to operate said diaphragm and close said valve whereby the flow of air is switched through said transmission tube for driving 90 carriers.

4. In a pneumatic despatch tube apparatus, a tube for the transmission of carriers, a blower or pump, means for driving said blower or pump, a connection between 95 said blower or pump and said transmission tube, a branch tube or air inlet in communication with said connection, a valve adapted to control the flow of air through said air inlet, a diaphragm connected with said valve 100 and adapted to be actuated by the blower on one side to hold said valve normally open thereby short-circuiting the flow of air to and relieving the load upon said blower, a normally closed passage connecting the opposite side of said diaphragm with said blower, means for opening said passage 105 to operate said diaphragm and close said valve whereby the flow of air is switched through said transmission tube for driving carriers, 110 and means for timing the closure of said passage to permit said valve to resume its normal or open position.

5. In a pneumatic despatch apparatus, a tube for the transmission of carriers, a 115 blower or pump, a connection from said tube to said blower whereby air is exhausted from said tube, a branch tube provided with an air inlet and in communication with said connection, a chamber formed in said branch tube, a diaphragm in said chamber, a valve arranged to close said air inlet and connected on said diaphragm, a second connection from said chamber on the other side of the diaphragm from the branch tube to said 120 exhaust connection, a valve in such second 125

connection, means connected to said valve to operate the same, said means being arranged to open the valve upon the introduction of a carrier into the transmission tube and to then close said valve, and means controlling the operation of said first means in closing said valve.

5 In testimony whereof, I have signed my

name to this specification in the presence of 10 two subscribing witnesses, this nineteenth day of March A. D. 1908.

JAMES G. MACLAREN.
